US00D950573S

(12) **United States Design Patent** (10) Patent No.: **US D950,573 S**
Anzures et al. (45) Date of Patent: **** May 3, 2022**

(54) **DISPLAY SCREEN OR PORTION THEREOF WITH GRAPHICAL USER INTERFACE**(71) Applicant: **Apple Inc.**, Cupertino, CA (US)(72) Inventors: **Freddy Anzures**, San Francisco, CA (US); **Stephen O. Lemay**, San Francisco, CA (US); **Marcel van Os**, San Francisco, CA (US)(73) Assignee: **Apple Inc.**, Cupertino, CA (US)(***) Term: **15 Years**(21) Appl. No.: **29/583,590**(22) Filed: **Nov. 7, 2016****Related U.S. Application Data**

(60) Continuation of application No. 29/497,631, filed on Jul. 25, 2014, now Pat. No. Des. 771,119, which is a continuation of application No. 29/409,459, filed on Dec. 22, 2011, now Pat. No. Des. 709,911, which is a continuation of application No. 29/354,107, filed on Jan. 19, 2010, now Pat. No. Des. 699,733, which is a division of application No. 29/282,840, filed on Jul. 30, 2007, now Pat. No. Des. 628,205, which is a continuation-in-part of application No. 29/281,695, filed on Jun. 28, 2007, now abandoned, which is a continuation-in-part of application No. 29/281,507, filed on Jun. 25, 2007, now Pat. No. Des. 608,366, which is a continuation-in-part of application No. 29/281,460, filed on Jun. 23, 2007, now Pat. No. Des. 604,305.

Primary Examiner — Melanie H Tung*(74) Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing our new design.

The dot-dash broken lines in the FIGURE show a display screen or portion thereof, and form no part of the claimed design. The dashed broken lines in the FIGURE show portions of the graphical user interface that form no part of the claimed design.
